UNITED STATES PATENT OFFICE.

OTTO J. GROEHN, OF DETROIT, MICHIGAN, ASSIGNOR TO CLAYTON AND LAMBERT MANUFACTURING COMPANY, OF DETROIT, MICHIGAN, A CORPORATION OF MICHIGAN.

WIDE-MOUTH TORCH BURNER.

1,420,697.

Specification of Letters Patent. Patented June 27, 1922.

Application filed April 25, 1921. Serial No. 464,332.

To all whom it may concern:

Be it known that I, Otto J. GROEHN, a citizen of the United States of America, residing at Detroit, in the county of Wayne and State of Michigan, have invented certain new and useful Improvements in Wide-Mouth Torch Burners, of which the following is a specification, reference being had therein to the accompanying drawings.

10 This invention relates to torch burners and refers more particularly to a new and improved construction adapted for blow torches or the like.

15 Among the objects of the invention are to provide a torch having a more efficient combustion chamber than those now in use; to provide a torch in which the liability of the torch to produce incomplete combustion is minimized and in general to provide a new and improved torch burner of the character above mentioned. The invention also resides in the novel arrangement of the top deflecting wall or plate and in such further features of construction and arrangements 25 and combinations of parts as will more fully hereinafter appear.

In the drawings:

Figure 1 is a top plan view of a torch embodying my invention;

30 Figure 2 is a vertical cross-section on the line 2—2 of Figure 1.

Describing in detail the particular embodiment of my invention shown in the drawings, A designates a torch burner which is provided at its side with a fitting A' whereby it is supported by a pipe or standard A² upon the tank A³. In blow torches of this general character means is provided for forcing the fuel from the tank out of 40 a discharge orifice toward or into a combustion chamber and the present invention relates primarily to the burner construction.

Describing now in detail the burner B designates a preheating chamber in which the fuel coming from the tank A³ through the pipe A² is first preheated before passing the control valve C. In order to get from the chamber B to the port C' it is necessary for the fuel to pass through the tube B² and thus be carried adjacent the lower wall of the combustion chamber D and from here the fuel passes through the port C', passage-way E through the discharge nozzle E'. The latter is preferably carried by a removable fitting E² and an adjustable member F is

provided which has a pin F' normally out of contact with the discharge nozzle E' but adapted when adjusted forward to clean any carbon or other obstruction which might accumulate on the discharge nozzle.

After passing from the discharge nozzle the fuel mixed with the air is forced into the chamber D in which combustion takes place and it is the primary object of this invention to provide a new and improved construction and arrangement of combustion chamber. As shown in detail in Figure 2, the combustion chamber D has its top wall G provided with a downwardly inclined portion G' against which the fuel discharge from the nozzle E' strikes. This not only provides a hot spot or surface which will insure combustion but it also forces the hot gases down against the lower wall G² of the combustion chamber and thereby 75 greatly increases the vaporizing effect of the fuel coming through the preheating chamber B and its tube B². It will also be noticed that the combustion chamber D flares outwardly in a forward direction and terminates in a portion H having substantially parallel walls H'. By this arrangement a flame of any desired width or shape can be obtained, the particular shape shown in the drawings being particularly adapted for 80 burning off paint or other work of similar nature.

The burner is provided with the usual drip pan J for use in starting the torch. While I have shown the downwardly inclined wall G' as being used in connection with a wide flat type of discharge outlet, in the broader aspects the invention is not limited to the use of this feature with the particular novelty shown and various other 90 changes can be made without departing from the spirit of my invention.

What I claim as my invention is:

1. In a blow torch, a burner comprising a discharge orifice, a combustion chamber 100 located in advance of said orifice, said combustion chamber having a downwardly and forwardly inclined wall and having forwardly and outwardly inclined side walls.

2. In a blow torch, a burner comprising 105 a discharge orifice, a combustion chamber located in advance of said orifice, said combustion chamber having a downwardly and forwardly inclined wall and having forwardly and outwardly inclined side walls 110

terminating at the extreme forward end in substantially parallel side walls.

3. In a blow torch, a burner comprising a discharge orifice, a combustion chamber located in advance of said orifice, a pre-heating chamber located beneath the center of the combustion chamber, and means for directing the hot gases of combustion against one wall of said combustion chamber adjacent to the forward end of the pre-heating chamber.
4. In a blow torch, a burner comprising a discharge orifice, a combustion chamber located in advance of the orifice, a pre-heating chamber disposed beneath the center of said combustion chamber, valve controlled means extending from the pre-heating chamber for supplying a fuel to the orifice,

and means for deflecting the hot gases of combustion against one wall of said combustion chamber adjacent to the forward end of the pre-heating chamber.

5. In a blow torch, a burner comprising a discharge orifice, a combustion chamber located in advance of said orifice, a pre-heating chamber adjoining said combustion chamber, and a conduit in said preheating chamber adjacent to one wall of said combustion chamber and in communication with said discharge orifice, said combustion chamber having means for deflecting the heat against the wall thereof adjacent to said conduit.

In testimony whereof I affix my signature.

OTTO J. GROEHN.
